UNITED STATES PATENT OFFICE.

FRED BAHLER, OF GILROY, CALIFORNIA.

TENT-SUPPORT.

1,255,683.

Specification of Letters Patent.

Patented Feb. 5, 1918.

Application filed October 4, 1916. Serial No. 123,722.

To all whom it may concern:

Be it known that I, FRED BAHLER, a citizen of the United States, residing at Gilroy, in the county of Santa Clara and State of California, have invented certain useful Improvements in Tent-Supports, of which the following is a specification, reference being had therein to the accompanying drawing.

The invention relates to a foldable frame structure and more particularly to the class of foldable or collapsible tent supports or frames.

The primary object of the invention is the provision of a support of this character which serves as a frame or tent pole and is capable of folding or collapsing so that when the tent is not in use the support will be brought into compact form to occupy the least possible space and to permit the convenient carrying thereof or the bundling of the same with the tent covering.

Another object of the invention is the provision of a support of this character wherein the sections thereof are connected together in a novel manner so that they may be readily adjusted and folded and when set up for use will serve as a frame or pole for the tent.

A further object of the invention is the provision of a support of this character wherein the size thereof can be varied to meet the necessity of the capacity of the tent when set up for use, the support being of novel form to permit the folding thereof with despatch and the proper adjustment of the same.

A still further object of the invention is the provision of a support of this character which is extremely simple in construction, readily and easily folded or set up for use, thoroughly reliable and efficient in its purpose, strong, durable and inexpensive in manufacture.

With these and other objects in view the invention consists in the features of construction, combination of elements, and arrangement of parts as will be hereinafter fully described, illustrated in the accompanying drawing, and pointed out in the claim hereunto appended.

In the accompanying drawings:

Figure 1 is a perspective view of a tent showing the support, constructed in accordance with the invention in use, the tent being partly broken away.

Fig. 2 is a side elevation of the support.

Fig. 3 is a fragmentary vertical longitudinal sectional view through one hinge joint of the support.

Fig. 4 is a fragmentary side elevation showing sections adjacent each other of the support folded.

Similar reference characters indicate corresponding parts throughout the several views in the drawing.

Referring to the drawing in detail the support comprises a sectional substantially U-shaped frame A including the main bar or rail formed in a plurality of sections 5 and the end props or upright bars or rails 70 formed in sections 6 which are at right angles to said main bar or rail.

The outermost sections 5 of the plurality constituting the main bar or rail are fixed in any suitable manner to the innermost sections 6 with the props or uprights at their meeting ends. The sections 5 and 6 of said bars or rails are swingingly joined to each other at their meeting ends through the medium of detachable hinges each comprising 80 a pair of leaves or straps 9 formed with pintle sleeves 8 in which is engaged the pivot pintle or bolt 9 which is held therein by a wing nut 10 threaded thereon so that the leaves or straps 7 of the hinge can be readily 85 separated from each other in the adjustment of the support and when the leaves or straps 7 are joined will swingingly connect together the sections adjacent each other.

The leaves or straps 7 of the hinges are 90 detachably connected to the meeting ends adjacent to each other of the sections through the medium of bolts 11 which carry wing nuts 12. In this instance the leaves or straps 7 are formed with a plurality of 95 holes 13 for the reception of the bolts 11 which are reversely passed therethrough and also through suitable holes in the sections 5 and 6 of the frame A and in this manner any number of sections can be 100 swingingly joined to each other and readily adjusted as will be obvious.

The frame A can be readily folded by the swinging of the sections onto each other so as to render the frame compact when in 105 folded condition to occupy the least possible space while not in use.

The frame when set up for use is of substantially U-shape and the tent covering B is stretched thereover as shown in Fig. 1 of 110

the drawing and anchored at the ground or foundation in the usual well-known manner.

From the foregoing it is thought that the construction and manner of use of the tent support will be clearly understood and therefore a more extended explanation has been omitted.

What is claimed is:

- 10 In a device as described, in combination, two bars, two similarly shaped hinge leaves secured upon the respective bars so as to

permit the bars to contact endwise, a pintle passing through the beads of said hinge leaves, said pintle being threaded at one end, and a thumb nut engaging the threaded end of said pintle and adapted to jam the edges of said bars and also to jam the beads of said hinge leaves together so as to frictionally prevent the collapsation of said bars.

In testimony whereof I affix my signature.

FRED BAHLER.
